UNITED STATES PATENT OFFICE.

WALTER C. BAUER, OF LINDEN, NEW JERSEY, ASSIGNOR TO UPPERCU CADILLAC CORPORATION, A CORPORATION OF NEW YORK.

PISTON.

Application filed March 30, 1925. Serial No. 19,375.

To all whom it may concern:

Be it known that I, WALTER C. BAUER, a citizen of the United States, and a resident of Linden, in the county of Union and State of New Jersey, have invented certain new and useful Improvements in Pistons, of which the following is a specification, reference being had to the accompanying drawings, forming part of this specification.

10 This invention relates to pistons and more particularly to those used in conjunction with internal combustion engines.

The embodiment as herein disclosed features a piston of the composite type having 15 an inner or main portion formed of relatively soft thermally conductive material and an outer sleeve portion formed of relatively hard wear resisting material.

One of the objects of the present invention 20 is to provide a novel and improved piston of the type referred to in which the inner thermally conductive portion is so formed as to permit circumferential expansion of the same whilst preventing therein 25 radial distortion and its resultant detrimental effect upon the outer contiguous sleeve portion.

A further object of the invention is to 30 provide an improved form of piston in which the wrist pin bosses are formed as an integral part of the outer or harder portion, the parts being so fabricated as to permit the bosses to extend through the inner thermally conductive portion in a manner 35 as to allow separation of the parts.

A still further object of the invention is 40 to provide a piston having the features above described in which the parts are few and so constructed that they can be readily assembled or disassembled, thus permitting the replacement of any of the parts.

Composite pistons having several parts 45 respectively formed of non-analogous material are known in the art and have been found to possess certain advantages over the type in common use. Pistons of this type, however, usually have the wrist pin bearing formed as part of the main or heat conducting portion which must necessarily

be formed of an alloy not high in tensile 50 strength.

This relatively soft portion being disposed so as to absorb and dissipate the heat generally by the explosion, also directly receives the full effect of the explosive force which 55 must be transmitted to the wrist pin bearings in the operation of the motor. Therefore, the common practice of having these bearings part of the aforesaid relatively soft portion is manifestly a disadvantage which 60 has been obviated by my improved construction in the present invention.

Composite pistons having heat conducting properties are usually provided with a skirt or sleeve portion adapted to resist 65 wear and which surrounds the main body portion. This main body portion being exposed to a high degree of heat and having great expansive characteristics due to the nature of the alloy employed in the manufacture of the same, must necessarily be subject to considerable circumferential expansion, and where no provisions have been made to the contrary this circumferential expansion results in radial distortion which 70 reacts upon the relatively thin sleeve portion. This invention, however, provides improved means permitting expansion of this member 75 without any appreciable effect upon the sleeve portion.

To these and other ends, the invention consists in certain improvements and the combination and arrangement of parts, all as will be more fully hereinafter described, the features of novelty being pointed out 80 particularly in the claims at the end of the specification.

In the drawings:

Figure 1 is a vertical section of the preferred form of my invention showing the 85 parts in their assembled relation.

Figure 2 is a vertical section taken at right angles to that of Fig. 1.

Figure 3 is a vertical section illustrating a modified embodiment of the form shown 95 in Figs. 1 and 2.

Figure 4 is a vertical section taken at right angles to that of Fig. 3.

In the present instance with reference to Figs. 1 and 2, 10 designates the main body portion of the piston preferably formed of an aluminum alloy to which is attached a 5 sleeve or skirt 11 preferably constructed of cast iron. The parts 10 and 11 are held in their assembled relation by the retaining nut 12 which engages the body portion 10 by means of the screw threads.

10 On the skirt portion 11, which as has been said, is preferably constructed of cast iron, there are formed the wrist pin bosses 13, connected by a bridge 13^a.

15 The body portion 10 is provided with openings 14 which are disposed diametrically opposite one another and extend to the lower edge. These openings provide the necessary clearance for the wrist pin bosses 13 and bridge 13^a which extend through 20 the aluminum body, in addition to which these openings permit said body portion to expand circumferentially without causing any radical distortion therein.

25 The skirt portion 11 can be made relatively thin and so constructed as to snugly fit the interior of the cylinder, there being no danger of binding at this point due to the openings 14 which effectively prevent expansion of the aluminum body and its 30 contiguous skirt portion. In this manner I have eliminated the objectional piston slap incidental to the operation of engines provided with pistons having a sloppy fit.

35 As shown in the drawings, I have provided a clearance 15 between the body and the skirt with a suitable gap or opening 16 to permit the oil to enter between these walls, it having been found that the oil materially assists in conducting the heat 40 away from the main body portion. The openings 14 provide the necessary drainage for the oil in addition to which suitable apertures 17 may be formed in the lower portion of the body 10 for this purpose.

45 With reference to Figs. 3 and 4 there is shown alternative construction in which the wrist pin bearings 13 are formed as part of the main body portion 10, the openings 14 still being retained in the body 10 to permit 50 circumferential expansion. The sleeve portion 11 may be provided with the bridge 13^a to give added strength or dispensed with when a floating wrist pin is contemplated.

55 It should be noted that the piston as herein shown and described comprises two main parts of light and simple construction which are readily assembled by slipping one part over the other and securing them in fixed relation by the retaining nut.

60 Variation may be resorted to within the scope of the invention and portions of the improvements may be used without the others whilst not departing from the spirit of the invention.

Having thus described my invention, I claim:—

1. A piston comprising, an inner body portion, an outer sleeve portion having wrist pin bearings integral therewith, said wrist pin bearings extending through said body portion in a manner as to permit separation 70 of the parts.

2. A piston comprising, an inner body portion provided with openings, an outer sleeve portion having wrist pin bearings integral therewith, said bearings extending through said body portion by means of the openings therein in a manner as to permit separation of the parts, and a means to retain 75 said portions in assembled relation. 80

3. A composite piston including, a body portion formed of thermally conductive material, a sleeve portion formed of relatively hard material mounted on the body portion, wrist pin bearings formed integral with the sleeve portion, said body portion provided with means to permit circumferential expansion thereof without radial extension, and means to retain said portions in assembled 85 relation in a manner as to permit separation 90 of the parts.

4. A composite piston comprising, a main body formed of thermally conductive material, said body provided with means adapted to permit circumferential expansion of the 95 lower portion thereof without radial extension, a sleeve portion formed of relatively hard wear resisting material secured to said lower portion of the body, and wrist pin 100 bosses formed integral with said sleeve portion and extending through said body.

5. A composite piston comprising, an inner main body, said body provided with means comprising cut away portions forming openings adapted to permit circumferential expansion of the lower portion thereof without causing radial extension, an outer sleeve secured to said lower portion of the body, and wrist pin bosses formed integral with the sleeve portion and extending through the inner main body, the whole 105 adapted for the separation of the parts. 110

6. A composite piston comprising, a main body having a lesser and a greater diameter, a sleeve portion externally of the main body and contiguous with the greater diameter, wrist pin bearings integral with the sleeve portion, said main body having portions cut away to permit circumferential expansion thereof and to further permit the wrist pin 115 bearings to pass through said body. 120

7. A piston of the class described, comprising a main body having diametrically opposite portions cut away to provide openings which extend from the lower edge to a point intermediate its ends, a sleeve portion disposed externally of said body and contiguous with a portion thereof, wrist pin 125

bearings integral with the sleeve portion and extending through said body by means of said openings, and a retaining member adapted to hold the parts in operative relation.

5. 8. In a piston, the combination of a main body portion, a sleeve member disposed externally thereof and having a portion extending through said body portion, means on 10 the body portion comprising peripheral interruptions adapted to permit circumferential expansion of the body without radial distention.

15. 9. In a piston, the combination of a main body portion, an outer relatively thin sleeve having contact therewith and having an integral portion extending through said body portion by means of circumferential interruptions formed in the body adapted to permit 20 expansion of said body without creating radial pressure upon the sleeve portion.

25. 10. In a composite piston, the combination of a main body portion, an outer relatively thin contiguous sleeve having a portion extending through said body by means of openings formed in the body which extend

from its lower edge to a point intermediate the two ends, said openings adapted to permit expansion of the body without effect upon its contiguous sleeve portion.

30

11. In a composite piston, the combination of a main body portion having a series of ring grooves near its upper extremity, an outer contacting relatively thin sleeve mounted thereon in a manner as to expose 35 the ring grooves and to provide a clearance between said body and sleeve; said clearance extending from the upper edge of the sleeve portion downwardly to a point intermediate its upper and lower edges, the main body 40 portion being provided with openings to permit circumferential expansion of said body without causing radial distention of the sleeve portion, and a portion integral with said sleeve extending diametrically through 45 the body portion by means of said openings therein.

Signed at New York city, in the county of New York and State of New York, this 20th day of March, A. D. 1925.

WALTER C. BAUER.
